UNITED STATES PATENT OFFICE.

ACHSA C. WRIGHT, OF SUPERIOR, WISCONSIN.

RUG-MACHINE.

1,366,624.

Specification of Letters Patent. Patented Jan. 25, 1921.

Application filed May 26, 1919. Serial No. 299,908.

To all whom it may concern:

Be it known that I, Mrs. ACHSA C. WRIGHT, a citizen of the United States, residing at Superior, 1907 Lackawanna Ave., 5 in the county of Douglas and State of Wisconsin, have invented certain new and useful Improvements in Rug-Machines, of which the following is a specification.

The invention has for an object to provide 10 a simple machine adapted to facilitate the preparation of warp material for rug-making looms. It is a particular object of the invention to give a means adapted to use in threading upon a plurality of needles at 15 one time, pieces of cloth, forming, or to be formed into small squares which are to be threaded upon a warp strand. It is also an aim to give a means for cutting a plurality of squares at one time from a strip 20 of cloth already threaded upon a plurality of needles. Another object of the invention is to give an improved means for holding a number of needles releasably and in a manner to permit rapid manipulation and 25 adjustment of the needles as required.

Additional objects, advantages and features of invention will appear from the construction, arrangement and combination of parts hereinafter set forth and shown in the 30 drawings, wherein,

Figure 1 is a side elevation of a machine constructed in accordance with my invention,

Fig. 2 is a front view,

Fig. 3 is a top view,

Fig. 4 is a detail of one of the needle holders,

Fig. 5 is a side elevation of a modified form of the device.

Fig. 6 is a detail of a modified needle.

There is illustrated a needle holding device comprising two blocks 10 and 11, the latter being carried upon a suitable stand 12, while the block 11 is provided with pins 45 13 engaged slidably in suitable holes 14 formed in the block 10. At each side fastenings 15 are provided by which the blocks may be held closely clamped together. As shown in Fig. 4, the blocks are provided

50 with opposed grooves 16, wherein needles 17 may be adjusted and clamped when the blocks are secured in closed relation. If desired, a series of small needle retaining springs 18 may be secured upon the block 10 while a suitable channel 19 is formed in

the block 11 to accommodate the springs so as to permit the blocks to come into close engagement with the needles without interference. Upon the block 11 there are mounted a multiplicity of knives or blades 20, 60 having horizontally extended blades disposed in vertical planes over the block 10, extending beyond the needles a distance when the blocks are in closed position. The blades are formed of sheet metal, having 65 ears 21 at their lower sides bent at right angles and secured upon the block 11 by screws as shown. Pivoted upon each of the blades 20 there are upper blades 22, having at their back edges ears 23 secured upon a 70 cross bar 24 by which all of the knives are caused to move together, this bar being operated by means of a handle 25 suitably secured thereon.

Hinged upon the edge of the block 10 opposite the bases of the knives 20 there is a plate 26, having a multiplicity of pressers 27 arranged in pairs adapted to pass closely beside respective needles, this block having an operating handle 28 by which it may be 75 swung upwardly and inwardly over the block 10 to bring the pressers 27 down beside the needles 17.

In the lower part of the stand 12 a rack 29 may be provided for holding spools 30 85 of warp thread, the ends of which are threaded in respective needles 17, as shown. The pressers 27 are so located upon the plate 26 that at one position the pressers will lie horizontally immediately above the level of 90 the upper edges of the blade 20, and upon further movement they will pass downwardly below such level, as will be understood.

In its simplest form, the needles 17 may 95 be held vertically between the blocks 10 and 11 as indicated in Fig. 1, and in the use of this device strips of cloth of proper width are laid longitudinally across the series of needles and the knives 20 operated to cut the 100 cloth centrally between the needles, leaving small squares upon each of the needles, as will be understood. The plate 26 is then operated to bring the pressers into engagement with the severed cloth, pressing it 105 downwardly upon the needles, or the pressers may be operated occasionally to press a number of layers of fabric down at one time.

In Fig. 5 there is shown an adaptation of the device to facilitate the placing of cloth 110

upon the needles, in this instance, the needles being given an inclination by forming the opposed faces of the blocks 10' and 11' corresponding to the blocks first described, 5 at a suitable angle to the perpendicular, and the pressers 27^a, corresponding to those 27 before mentioned are formed with shoulders 30, positioned to fall at a proper distance from the series of needles when the 10 pressers are swung inwardly as before mentioned. The plate 26' corresponding to the one 26 before mentioned is so hinged to the block 10' that it may fall in open position with the pressers 27^a inclined outwardly as 15 dotted at the right in Fig. 5, so that a piece of cloth laid across the outer ends of the pressers and against the shoulders 30 will be retained by gravity, thus readily adapting the machine to receive strips of cloth 20 from a strip cutting machine, or permitting manual feeding of the strips, as found preferable. The inclination given the needles is such that at the instant the pressers 27^a pass inwardly of the points of the needles, the 25 planes of the pressers and needles will be at right angles to each other, and under further movement of the pressers the cloth will slide outwardly on the pressers to some extent, although this sliding movement is not 30 essential.

If found preferable the needles may be formed with a curve as shown in Fig. 6, at their outer parts only.

In the operation of the machine, when a 35 sufficient quantity of fabric has been threaded upon the needles, the fastenings 15 may be released, and the needles lifted from place and the fabric thereon passed inwardly onto the warp thread, after which the needles are returned to their places and secured 40 between the blocks as before, permitting further operation of the machine to refill the needles, these operations being repeated

until a length of warp material is provided sufficient to be placed in a loom. 45

What is claimed:

1. A machine for threading a multiplicity of rug segments simultaneously, comprising means for releasably holding a plurality of needles in position to receive fabric, cutter blades therebetween, fabric pressing means operative between the needles and blades, and a second series of blades coöperative with the first for cutting a length of fabric threaded upon the needles. 55

2. A device of the character described, comprising relatively movable needle clamping blocks, means to secure the blocks in clamping position, a plurality of needles held therebetween, knives carried by one of the blocks extending between the needles, movable knives coöperative with the first knives for cutting fabric pierced by the needles, and a fabric pressing device for engaging fabrics upon the needles. 65

3. A device of the character described comprising a stationary element, a movable element coöperative therewith to clamp a series of needles, cutter blades carried by one of the two first elements named, a second series of blades coöperative with the first mounted for simultaneous movement to sever cloth pierced by the needles and disposed over the first named blades, and an element pivoted at the side of said stationary element opposite the second named element, including a plurality of pressers adapted to pass between the needles and first named blades upon inward movement of the pivoted element. 75

In testimony whereof I have affixed my signature in presence of two witnesses.

MRS. ACHSA C. WRIGHT.
